UNITED STATES PATENT OFFICE

2,554,071

PULVERIZER HAVING A TWO-PART
HOUSINGOrval R. Strawn, Columbus, Ohio, assignor to
The Jeffrey Manufacturing Company, a corpora-
tion of Ohio

Application July 9, 1949, Serial No. 103,817

6 Claims. (Cl. 241—285)

1

This invention relates to a pulverizer or crusher, and an object of the invention is to provide such a device in which the housing which provides the reducing chamber is made up of two principal parts both mounted on a common base, in which one of the parts carries the breaker plate and the feed chute, and the other part supports the material reducing rotor, and in which the second part is adjustable either pivotally or slidably relative to the first part so as to remove the rotor substantially entirely from the first part and to expose it for ready access to the hammers and the like.

Other objects of the invention will appear hereinafter, the novel features and combinations being set forth in the appended claims.

In the accompanying drawings,

Fig. 1 is a side elevational view of one form of hammer mill type crusher involving my invention;

Fig. 2 is a sectional elevational view of the device of Fig. 1;

Fig. 3 is an elevational view of the machine of Fig. 1, with parts broken away for clarity;

Fig. 4 is a sectional view of a modification of the machine shown in Figs. 1, 2 and 3; and

Fig. 5 is an enlarged elevational sectional view showing a modification of the adjusting means for one of the rotor bearings.

As illustrated in Figs. 1, 2 and 3 of the drawings, the crusher or hammer mill includes a base 10 upon which an enclosing housing 11 is formed which provides a reducing chamber of the crusher within which there is a rotor 12 that rotates upon an axis extending transversely of the housing and reducing chamber. Except for differences hereinafter pointed out, the general arrangement of the crusher is that frequently found in prior art hammer mills so that many of the parts need not be individually described.

The housing 11 is formed of two principal parts, the first part being designated 13 and the second part 14. The first part 13 carries a breaker means 15 against which material being reduced is broken after being struck and impelled by the hammers of the rotor 12. This part 13 also provides a top feed opening 16 and feed chute 17. The second part 14 of the casing supports the rotor 12 by virtue of a pair of bearings enclosed in bearing boxes, one of which is seen at 18. Each of said bearing boxes is adjustably mounted on a side of the housing section 14 by flexible adjusting means including a plate 19 (see Figs. 1, 3 and 5) having a cup 20 receiving a boss on the bottom of the bearing box 18, the bearing box 18 being clamped to said plate 19 by a U-

1

shaped yoke 21. Plate 19 is adjustably supported upon a vertically adjustable threaded rod 22 which is directly below the cup 20 and which is adjustably mounted on a bracket 23 formed as an integral part of the housing section 14.

At opposite ends the plate 19 has downwardly extending adjusting threaded rods 24 provided with adjusting nuts which are primarily for adjusting the level of the plate 19 on the supporting rod 22. In the form of this adjusting mechanism, as illustrated in Fig. 5 of the drawings, instead of a single bracket 23 there is a top plate 25 which rests on the bracket and which can be adjusted forwardly and rearwardly by a threaded rod 26 integrally attached to said plate 25 and adjustable by a pair of nuts on opposite sides of a bracket 27 through which the rod 26 extends, which bracket 27 is attached to a side plate of the housing section 14. In this construction the top plate of the bracket 23 is provided with elongated slots through which the rods 22 and 24 extend, against which they are clamped together with the top plate 25 by nuts on opposite sides of them which are threaded on the rods 22 and 24, respectively.

The section or part 14 of the housing 11 also carries a bottom screen 28 which, per se, is of generally standard construction and may also be provided with a tramp material bin 29. The complete part of section 14, including the rotor 12 which it supports, is adjustably mounted for sliding or rolling rectilinear movement on the base 10 so that it can be adjusted to provide a reducing housing with the rotor 12 therein, as illustrated in Fig. 1 of the drawings, or can be separated so that the rotor 12 is readily accessible for inspection or repair and particularly for the removal or reversal of the swing hammers. To this end there is a pair of anti-friction rollers 30 on each side of the housing section 14 at the bottom adapted to roll on guides on the base 10.

To effect adjustment of the two sections 13 and 14 of the housing relative to each other and to move the rotor out of the fixed portion 14 of the housing 11 while maintaining its axis parallel to that position in which it operates to reduce material, there is a pair of threaded rods 31, one on each side of the frame, each of which is held in a bracket 32 attached to the housing part 14 by appropriate collars and which threads into a receiving lug 33 attached to an upright side plate of the housing section 14.

The two rods 31 are operated by ratchet tools 34 which are interconnected by a cross-rod 35 to insure uniform movement of both sides of the

housing section 14 as it is adjusted toward or from the housing section 13.

From the above description it is manifest that the two sections 13 and 14 of the housing may be brought together to form the complete housing 11 with a reduction chamber for the rotor 12, or they may be separated to provide ready access to the rotor 12 without completely removing any of the parts of either housing section.

In Fig. 4 of the drawings a crusher is illustrated which except for differences specifically pointed out will be understood to follow that of Figs. 1, 2, and 3. In general, the difference lies in the fact that the second part of the housing is adjusted away from the first part by swinging it or pivoting it rather than sliding it or moving it rectilinearly. Certain parts of the crusher of Fig. 4, particularly the bearing boxes and adjusting means, are not shown because they are the same as those seen in Figs. 1 through 3.

The crusher of Fig. 4 includes a base 110 upon which there is a housing 111 made up of the two parts or sections 113 and 114. Housing part 113 is provided with breaker means 115 and with a feed opening 116 and feed chute 117. A rotor 12 identical with the previously described rotor 12 is mounted upon the bearings in box 18. Housing section 114 is pivotally mounted on the base 110 about a transverse horizontal axis provided by pivot means 36. At each side of the casing 114 there is a segmental worm gear 37 which is attached to the adjacent portion of the housing section 114 so that upon rotation of said two gear segments 37 the housing section 114 will be rotated upon bearings (not shown) associated with the shaft 36. To effect this rotation there is a worm 38 carried in a gear housing 39 attached to the base 110. Operation of each worm gear 38 is through a rotatable shaft 40 which is comparable to the previously described shaft 31, the two shafts 40 being operable by ratchet tools 34 and an interconnecting cross-rod 35 substantially identical with the operating means of shaft 31 above described.

It is obvious that by adjusting the shafts 40 the housing section 114 together with the rotor 12 carried thereby may be pivotally adjusted so as to form a complete housing, with the rotor 12 in the reduction chamber formed thereby, or said housing section 114 may be pivoted to expose the rotor 12 for ready inspection or repair as above described.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A hammer mill including a base, a two part housing mounted on said base providing a reducing chamber, one of said housing parts being fixed to said base and including a feed chute, said other housing part being movable upon said base to separate said housing parts, a rotor in said reducing chamber having material reducing hammers and rotating upon an axis extending transversely of said housing and reducing chamber, bearing means carried by each of opposite walls of said movable housing sup-

porting opposite ends of said rotor, breaker means on said fixed housing part in said reducing chamber below said feed chute and extending parallel to the axis of said rotor, screen means on said movable housing part in said housing and below said rotor, and mechanism for moving said movable housing part, bearing means, rotor and screen means whereby said rotor axis moves laterally from its operating position while remaining substantially parallel with respect thereto and said parts carried by said movable housing part are removed from said fixed housing part and exposed for ready access, said mechanism including a pair of spaced screw means, one adjacent each of said opposite side walls of said movable housing part, and operating mechanism interconnecting said screw means for rotation together.

2. A hammer mill including a base, a two part housing mounted on said base providing a reducing chamber, one of said housing parts being fixed to said base and including a feed chute, said other housing part being movable upon said base to separate said housing parts, a rotor in said reducing chamber having material reducing hammers and rotating upon an axis extending transversely of said housing and reducing chamber, bearing means carried by each of opposite walls of said movable housing supporting opposite ends of said rotor, breaker means on said fixed housing part in said reducing chamber below said feed chute and extending parallel to the axis of said rotor, screen means on said movable housing part in said housing and below said rotor, and mechanism for moving said movable housing part, bearing means, rotor and screen means whereby said rotor axis moves laterally from its operating position while remaining substantially parallel with respect thereto and said parts carried by said movable housing part are removed from said fixed housing part and exposed for ready access.

3. Material reducing apparatus including a base, a two part housing mounted on said base providing a reducing chamber, one of said housing parts being fixed to said base and including a feed chute, said other housing part being movable upon said base to separate said housing parts, a rotor in said reducing chamber having material reducing elements and rotating upon an axis extending transversely of said housing and reducing chamber, bearing means carried by each of opposite walls of said movable housing supporting opposite ends of said rotor, breaker means on said fixed housing part in said reducing chamber below said feed chute and extending parallel to the axis of said rotor, and mechanism for moving said movable housing part, bearing means and rotor whereby said rotor axis moves laterally from its operating position while remaining substantially parallel with respect thereto and said parts carried by said movable housing part are removed from said fixed housing part and exposed for ready access.

4. Material reducing apparatus including a base, a two part housing mounted on said base providing a reducing chamber, one of said housing parts being fixed to said base and including a feed chute, said other housing part being movable upon said base to separate said housing parts, a rotor in said reducing chamber having material reducing elements and rotating upon an axis extending transversely of said housing and reducing chamber, bearing means carried

by each of opposite walls of said movable housing supporting opposite ends of said rotor, breaker means in said reducing chamber below said feed chute and extending parallel to the axis of said rotor, and mechanism for moving said movable housing part, bearing means and rotor whereby said rotor axis moves laterally from its operating position while remaining substantially parallel with respect thereto and said parts carried by said movable housing part are removed from said fixed housing part and exposed for ready access.

5. Material reducing apparatus including a base, a two part housing mounted on said base providing a reducing chamber, one of said housing parts being fixed to said base and including a feed chute, said other housing part being movable upon said base to separate said housing parts, a rotor in said reducing chamber having material reducing elements and rotating upon an axis extending transversely of said housing and reducing chamber, bearing means carried by each of opposite walls of said movable housing supporting opposite ends of said rotor, breaker means on said fixed housing part in said reducing chamber below said feed chute and extending parallel to the axis of said rotor, and antifriction roller means at each of said opposite sides of said movable housing part supporting it upon said base for rectilinear movement whereby said movable housing part, bearing means and rotor are movable laterally and the axis of said rotor remains substantially parallel with respect to its operating position and said parts carried by said movable housing part are removed from said fixed housing part and exposed for ready access.

6. Material reducing apparatus including a base, a two part housing mounted on said base providing a reducing chamber, one of said housing parts being fixed to said base and including a feed chute, said other housing part being movable upon said base to separate said housing parts, a rotor in said reducing chamber having

material reducing elements and rotating upon an axis extending transversely of said housing and reducing chamber, bearing means carried by each of opposite walls of said movable housing supporting opposite ends of said rotor, breaker means on said fixed housing part in said reducing chamber below said feed chute and extending parallel to the axis of said rotor, and pivot means at each of said opposite sides of said movable housing part supporting it upon said base for movement whereby said movable housing part, bearing means and rotor are movable laterally and the axis of said rotor remains substantially parallel with respect to its operating position and said parts carried by said movable housing part are removed from said fixed housing part and exposed for ready access.
